UNITED STATES PATENT OFFICE.

EUGENE V. MYERS, OF EAST ORANGE, NEW JERSEY, ASSIGNOR TO A. SCHRADER'S SON, INCORPORATED, OF BROOKLYN, NEW YORK, A CORPORATION OF NEW YORK.

TIRE VALVE.

Original application filed May 22, 1917, Serial No. 170,179. Divided and this application filed March 25, 1921. Serial No. 455,621.

This application is a division of my co-pending application, Serial No. 170,179, filed May 22, 1917, and is directed to one form of the tire valve stem set forth therein.

5 Valves for pneumatic tires usually comprise a long casing member commonly called a valve stem which is provided with a bore from end to end. The maximum diameter of such casings is limited due to the condition 10 that the valve must pass through a hole in the vehicle rim, and such hole is limited in size. Hence the internal bore must necessarily be of small dimensions. In those constructions wherein the valve casing is 15 provided with a reduced nipple at its inner end the diameter of this bore is still further limited.

Within the bore is usually located a valve seat and a valve plunger, together with a 20 spring for operating the plunger, and these parts are customarily made separately and inserted within the bore by screwing them in.

The valve casings as thus described have 25 almost invariably been made of brass owing to the fact that the valves in use are subjected to wet and moisture and would speedily rust if not formed of a non-rusting metal. It is particularly desirable that 30 the inner parts of the valve casing and particularly the portions near the inner end shall be rust-proof, since it is at these portions that the actual working parts of the valve are located. It has also been cus- 35 tomary to nickel-plate the casings but it is found in practice that the nickel-plating does not extend to any material extent into the bore of the valve casing.

The most expensive part of the valve is 40 the casing and it materially increases the cost thereof to construct it of brass or other expensive non-corroding metal. The object of the present invention is to reduce the cost of the casing by forming it at least in part 45 of steel or other cheap metal in such manner as to avoid the deleterious effects of rust, particularly on the inner part of the casing.

In the drawings, I have shown one method of accomplishing this result.

Referring to the drawings:

50 Figure 1 is a side elevation of a valve stem embodying my invention.

Fig. 2 is an enlarged longitudinal sectional view of the foot portion thereof.

Referring to the drawings, let A indicate 55 the valve stem as a whole, and B the foot portion thereof. The valve stem may be made of any cheap oxidizable metal, such as iron or steel, while the foot portion is preferably made of some rust resisting metal, 60 such as brass. The foot portion, as disclosed, consists of a head B⁸ and an integral collar or flange B⁹, which is force fitted or otherwise mounted upon the sleeve B¹⁰, 65 which may be integral with the valve stem 65

A. When the foot portion B⁸ is mounted on the sleeve B¹⁰, without force fitting one part over the other, the sleeve may be upset on the under side of the foot portion, as shown at B¹¹, and a line of solder may be 70 employed at B¹¹ to form a leak-tight joint between the parts. However, when the foot portion is force fitted over the sleeve, a fluid-tight joint results from the flowing of 75 the metal during this operation.

This construction might be considerably varied, and is adaptable for metals of similar character.

While I have shown and described one form of the invention, it will be understood 80 that I do not wish to be limited thereto, since various changes can be made therein, without departing from the spirit of the invention.

What is claimed is:

85 A valve stem or the like comprising a shell and a flange which forms the foot portion of the stem, the shell having a reduced sleeve at its inner end and the flange having a sleeve which is force fitted over the sleeve 90 on the shell and forming a leak-tight joint between the parts.

In witness whereof, I have hereunto signed my name.

EUGENE V. MYERS.
